UNITED STATES PATENT OFFICE

JOHN EDWARD HANNY, OF OREGON CITY, OREGON, ASSIGNOR TO CROWN WILLAMETTE PAPER COMPANY, OF SAN FRANCISCO, CALIFORNIA, A CORPORATION OF DELAWARE

METHOD AND MEANS FOR STORING PAPER PULP COMING FROM THE WET MACHINE

Application filed August 5, 1929. Serial No. 383,500.

The object of my invention is to provide means for accomplishing in a more practical and economical mode the storing, at a distant point, of the pulp for paper making as it comes from the wet machine. My purpose is to effect such storage in the form of a lightly packed pile, from which portions may be readily taken from time to time, for delivery to the storage tank of the paper making machine.

As well known in the art, the pulp for making paper is first converted into coarse sheets on the "wet machine" and then stored for later refinement, as required, for delivery to the storage tank of the paper making machine.

The present general mode of so storing coarse sheets of pulp consists in taking these sheets, as they come from the wet machine, and folding or "lapping" the same into small bundles called "laps"; then piling such laps in a stack from which later portions are taken to a shredder, so as to shred or reduce the laps into small particles, and the shredded material is then delivered to the storage tank of the paper making machine. Such method is both unduly expensive, and more or less destructive of an appreciable portion of the pulp. The un- due expense is caused by the necessity of having to truck the laps to the stack pile. The loss is occasioned by the laps stacking more or less in layers having air spaces between them, into which dust can enter.

And, it is further believed that the exposed margins of the laps provide more or less a suitable medium for the growth of bacteria. So frequently, before the laps are removed from the stack, their edges become discolored to such an extent that their surfaces must be scraped off; and such discoloration tends to spread throughout the body of the laps, so that laps which have been stored for some time can only be used up in small quantities, by being distributed in fresher pulp; and even then the grade of paper produced is frequently lowered.

My improved method consists in taking relatively small portions of the coarse pulp as delivered by the wet machine—these

small portions being known in the trade as "noodles"—and depositing such noodles on a belt conveyor, from which the noodles are discharged into a blast of air moving at high velocity, and discharging through a charger, by which the noodles are disintegrated into small particles; and the blast of air then functions further to carry the disintegrated pulp, in the form of small particles, to a distant point, where the material is discharged in the form of a spray to form a pile for storage. It will thus be seen that only the work of discharging the noodles of the pulp delivered from the wet machine into said blast of air discharging through said charger is required. No supplementary shredding devices are required; and the shredding of pulp into the desired small particles and storing of the latter at the distant point is accomplished in a single operation.

Furthermore, tests from moisture content of the pulp as it comes from the wet machine and as it is discharged by the blast of air at the place of storage, show that the pulp loses an appreciable amount of moisture; that is, such tests have shown that the moisture content of the paper pulp while on the conveyor belt is approximately 21.5% air dry, while after having been blown onto the pile at the place of storage is 24.9% air dry, which in my opinion promotes, to some extent the storing of the pulp in a loosely packed pile.

Furthermore by my method of storage, the pile of pulp is sealed on all sides, so that the interior of the pile is protected against deterioration from the causes mentioned.

Furthermore, the pulp from the wet machine is stored in the form of a lightly packed mass from which portions may be readily taken for delivery to the storage tank of the paper making machine. By the old method above described, in which the pulp coming from the wet machine is stored in the form of laps, these laps tend to pack down into a very solid mass, especially at the lower part of the pile so that the lower layers can frequently be removed only by the aid of a pick.

Furthermore, since by my improved method the pulp from the wet machine is stored in the form of a relatively lightly compressed mass, portions may be readily removed therefrom by sluicing by a suitable hydraulic pulp and the sluiced off pulp portions carried by the water emptied into a suitable ditch or trench, from which it may then be readily pumped to the storage tank 5 of the paper making machine.

10 The devices which I employ for carrying my method into practice, are hereinafter fully described with reference to the accompanying drawings.

15 In the drawings:

Fig. 1 shows a diagram of a combination of devices used by me for carrying out my improved storage method;

Fig. 2 shows a diagrammatic vertical section of the charger element of the pressure blower by which a continuous blast of air moving at high velocity is operatively applied to the masses of pulp or "noodles" dropped from the wet machine into said 20 charger;

Fig. 3 shows a top view of said charger; and

Fig. 4 shows a horizontal section through the charger on the line 4—4 of Fig. 3.

30 In Fig. 1 *a* represents a storage chest into which the screened stock coming from the grinders of the pulp mill is delivered. *b* represents a pump delivering through a pipe *c*, the stock from the storage chest to one or more wet machines *d*, or any sheet-forming equipment reducing the moisture content of the stock taken from the storage chest. The pulp is scraped from the press roll of the wet machine by means of a doctor 35 *e* as usual, and is dropped onto a belt conveyer *f* by which the scraped off portions of pulp or "noodles" are delivered to the charger *g* of the pressure blower *h*.

The charger *g* comprises, as shown by 45 Figs. 2 to 4, a hollow cylinder or drum 2 which is revolved by suitable means about a central vertical shaft 3. The interior of the drum is provided with radial vanes 4 thereby dividing the same into radially disposed 50 pockets 5.

The drum revolves between a stationary top plate 6 and a stationary bottom plate 7 and is rotated by any means as for example a chain *r*. An air tight sliding joint is understood to be provided between the revolving drum and the top plate.

The said top and bottom plates are respectively provided on one side with registering openings 8 and 9. These openings register 60 with the air blast inlet conduit *i* and the outlet conduit *j*.

The opposite side of the top plate is provided with an opening 11 over which is provided a hopper 12, into which the noo- 65 dles *p* carried by the belt conveyer *f* are

discharged, and thus dropped into one of the pockets of the drum, which pocket by the revolution of the drum is in the next instant placed in registration with the said air blast inlet and the outlet openings.

70 The conduit *i*, as shown by Fig. 1, is connected with the pressure blower *h* whereby an ample blast of air moving at high velocity is continuously discharged on the pulp carried by the registering pocket of the drum 2. As a result, the force of the blast of air striking the mass of pulp in such pocket, disintegrates or shreds the same into small particles, which are then blown out through the outlet 9 of the charger, into and 75 through the conduit *j*, and by the latter said particles are discharged in the form of a spray at the place of storage, making a pile 80 as represented by *q* in Fig. 1.

85 Preferably the discharge conduit *j* is provided with a nozzle *k* having a universal joint *m* permitting the nozzle to be manipulated as desired. In this way, the deposit of pulp may be controlled as convenient, and so as to make several piles if desired.

90 The mass of stored pulp is relatively lightly packed, so that portions thereof may later be readily removed for conveying to the storage tank of the paper making machine. Such removal may be effected by 95 sluicing, and the mass of removed pulp run into a pump pit *o* from which it may then be pumped by means of a pump *n* and conduit *s* to the storage tank of the paper making machine.

100 As mentioned, in the transit of the disintegrated pulp from the charger *g* through the discharging conduit *j*, the pulp loses an appreciable portion of its moisture content which in my opinion, has some bearing in 105 causing the discharged pulp particles to pack in the form of a relatively lightly compressed mass at the place of storage.

I claim:

1. Pulp storing means comprising, in combination, an air-pressure element adapted to generate a continuous blast of air moving at high velocity, said air-pressure element including a charger, means for delivering portions of pulp into said charger, said charger comprising a driven drum whose interior is divided into radially disposed pockets adapted successively to be positioned to receive the blast from said air-pressure element, means confining the discharge from said air pressure element to the inlet side of one of the pockets of said drum, and a conduit leading from the charger to a distant point.

110 2. Pulp storing means comprising, in combination, an air-pressure element adapted to generate a continuous blast of air moving at high velocity, said air-pressure element including a charger, means for delivering portions of pulp into said charger, said 115

120

125

130

- charger comprising a driven drum whose interior is divided into radially disposed pockets adapted successively to be positioned to receive the blast from said air-pressure element, a plate through which the air-pressure element discharges into the charger, an air tight joint between the inlet side of the pockets of said drum and said plate, and a conduit leading from the charger to a distant point.
- 5 3. Pulp storing means comprising, in combination, an air-pressure element adapted to generate a continuous blast of air moving at high velocity, said air-pressure element including a charger, means for delivering portions of pulp into said charger, said charger comprising a driven drum whose interior is divided into radially disposed pockets adapted successively to be positioned to receive the blast from said air-pressure element, a plate through which the air-pressure element discharges into the charger, an air tight joint between the inlet side of the pockets of said drum and said plate, a conduit leading from the charger to a distant point and the extremity of the conduit being provided with a jointed nozzle.
